DESIGN FOR A DECORATIVE MIRROR

Frank H. Nonnenbacher, Brooklyn, N. Y.

Application April 28, 1937, Serial No. 69,014

Term of patent 3½ years

To all whom it may concern:

Be it known that I, Frank H. Nonnenbacher, a citizen of the United States, residing at Brooklyn, in the county of Kings and State of New York, have invented a new, original, and ornamental Design for a Decorative Mirror, of which the following is a specification, reference being had to the accompanying drawing, forming part thereof, wherein—

Fig. 1 is a plan view of a decorative mirror showing my new design, and

Fig. 2 is a side elevation thereof.

I claim:

The ornamental design for a decorative mirror substantially as shown.

FRANK H. NONNENBACHER.
